UNITED STATES PATENT OFFICE.

CHARLES O. BUCKLAND, OF LAMPASAS, TEXAS, ASSIGNOR OF ONE-HALF TO ALONSON T. MITCHELL, OF LAMPASAS, TEXAS.

CARPENTER'S SQUARE.

1,100,530.

Specification of Letters Patent. Patented June 16, 1914.

Application filed February 27, 1914. Serial No. 821,420.

To all whom it may concern:

Be it known that I, CHARLES O. BUCKLAND, a citizen of the United States, residing at Lampasas, in the county of Lampasas and State of Texas, have invented a certain new and useful Improvement in 5 Carpenter's Squares, of which the following is a specification.

This invention relates to carpenters' 10 squares and has special reference to that type of carpenter's square commonly termed try square.

The principal object of the invention is to provide a try square having an improved 15 attachment thereto for laying off bevels at various angles.

Another object of the invention is to provide a try square of that class wherein the 20 arrangement will be such that by an improved means without disturbing the ordinary blade of the square a bevel may be laid off.

With the above and other objects in view 25 the invention consists in general of certain novel details of construction and combination of parts hereinafter fully described, illustrated in the accompanying drawings, and specifically claimed.

In the accompanying drawings, like characters of reference indicate like parts in the 30 several views, and:—Figure 1 is a side elevation of a square constructed in accordance with this invention, a certain cover plate being removed therefrom in order to show the 35 working parts of the invention. Fig. 2 is a section on the line 2—2 of Fig. 1. Fig. 3 is a view similar to Fig. 1 but showing all of the parts removed from the head.

In carrying out the objects of this invention there is provided a head 10 which may 40 be either of wood or metal and secured to this head is a steel blade 11, the blade being held in the head by the usual screws 12. The head 10 is cut away as at 13, at an angle of 45° so that when using the device for rough 45 work the part 13 may be set against the edge of a board or timber and the line drawn across said board or timber at 45°. The head 10 furthermore has a shallow recess 14 formed on one side thereof so that a cover 50 plate 15 may fit in said recess and lie flush with the side of the head. The usual protector plate 16 is also applied to the edge of the head and in this plate is formed a slot 55 17 which communicates with a recess 18

formed in the head beneath the cover plate. This recess 18 has extending up at its lower end a lug 19 and the recess is provided at its upper end with a shoulder 20. Leading from the recess at the upper end thereof is a 60 slot 21.

Adjacent the blade 11 the head is provided with a recess 22 wherein is received the hinge 23 of a bevel blade 24, the hinge revolving about a pintle 25. Extending from the blade 24 is an arc 26 and this arc 26 extends through the slot 17 and recess 18 and is movable into and out of the slot 21. This arc is furthermore provided at its inner end with an upstanding lug 27 arranged to engage the shoulder 20 when the blade 24 is at one limit of its movement. Between the lug 20 and the plate 16 is positioned the downwardly extending portion 28 of a lever 29, the lever being pivoted on a suitable pin 65 30 having its ends received respectively in said lug and plate. The lever 29 extends over the arc 26 and is provided with a finger 31 adapted to engage in one of a series of holes 32 formed in the arc 26, said holes being so positioned that when the finger is engaged in one or the other of the holes the blade 24 will lie at a desired angle to the blade 11, as for instance at such angle as to lay off a miter or octagon. In the lever 29 70 75 is formed a recess 33 and in the head 10 is a similar recess 34, a spring 35 fitting in these recesses and engaging the finger 31 against the arc 26 or into one of the holes 32. The end of the lever 29 is provided with a thumb piece 36 which projects through an opening 37 formed in the cover plate 15.

In using the device when the blade 24 lies against the head a right angle may be laid off but, when it is desired to lay a different angle the thumb piece 36 is pressed upon to move the finger 31 out of the hole wherein it lies. The blade 24 may then be rotated to the desired angle and the thumb piece released whereupon the spring 35 will cause 100 the finger 31 to enter a hole 32 and lock the blade in adjusted position.

There has thus been provided a simple and efficient device of the kind described and of the character specified.

Having thus described the invention, what is claimed as new, is:—

In a square of the class described, a head having a recess therein provided with a shouldered portion and with a slot leading 110

from the recess, a cover plate for said recess, provided with an opening, a lever pivoted in the recess and having a thumb piece extending through the opening, a blade pivoted to said head, an arc carried by said blade and provided with a series of spaced openings, a finger on said lever adapted to enter a selected opening in the arc to lock the blade in adjusted position, a lug on said 10 arc engageable with the shouldered portion

of the recess to limit the movement of the arc, a spring urging said finger into the openings in said arc, and a second blade fixedly attached to said head.

In testimony whereof, I affix my signature, in the presence of two witnesses.

CHARLES O. BUCKLAND.
